CHAISE LOUNGE OR THE LIKE

Marshall F. Adkins, Dallas, Tex.

Application September 30, 1947, Serial No. 141,663

Term of patent 3½ years

(Cl. D15—1)

To all whom it may concern:

Be it known that I, Marshall F. Adkins, a citizen of the United States of America, residing at Dallas, in the county of Dallas and State of Texas, have invented a new, original, and ornamental Design for Chaise Lounge or the like, of which the following is a specification, reference being had to the accompanying drawing, forming part thereof.

Figure 1 is a perspective view of a chaise lounge or the like, showing my new design; and

I claim:

The ornamental design for a chaise lounge or the like, substantially as shown.

MARSHALL F. ADKINS.
